UNITED STATES PATENT OFFICE

156,987

GOLF BAG CLIP

Robert E. Newton, San Francisco, Calif.

Application November 21, 1947, Serial No. 142,724

Term of patent 14 years

(Cl. D17—3)

To all whom it may concern:

Be it known that I, Robert E. Newton, a citizen of the United States, residing in the city and county of San Francisco, State of California, have invented a new, original, and ornamental Design for a Golf Bag Clip, of which the following is a specification, reference being had to the accompanying drawing, which forms a part thereof.

Fig. 1 is a plan view of a golf bag clip, showing my new design;

Fig. 2 is a front elevation;

Fig. 3 is a side elevation;

Fig. 4 is a rear elevation; and

Fig. 5 is an end view thereof.

I claim:

The ornamental design for a golf bag clip, as shown.

ROBERT E. NEWTON.
